(57) CLAIM

I claim the ornamental design for a bra, as shown and described.

DESCRIPTION

FIG. 1 is a rear, right perspective view of a bra, showing my new design;

FIG. 2 is a rear view thereof; and,

FIG. 3 is a rear, left perspective view thereof.

The broken lines are provided for environmental purposes only and form no part of the claimed design.

1 Claim, 3 Drawing Sheets
